PLACER MINING MACHINE

Application filed April 10, 1930. Serial No. 443,208.

This invention relates to improvements in placer mining machines of the type employed for removing gold and other valuable metals from sand or gravel.

5 It is the object of this invention to produce a power operated placer mining machine of such design and construction that it can be operated by one man and which shall be provided with means for separating the light or 10 flour gold from the heavier articles while the material is in a dry state.

The above and other objects which may become apparent as this description proceeds are attained by means of a construction and 15 arrangement of parts that will now be described in detail, and for this purpose reference will be had to the accompanying drawings in which the preferred embodiment of the invention has been illustrated, and in 20 which:

Fig. 1 is a side elevation of my improved placer mining machine;

Fig. 2 is a section through the separator that is employed in connection with the ma- 25 chine;

Fig. 3 is a side elevation partly in section, showing the sluice boxes;

Fig. 4 is a top plan view of a portion of one of the sluice boxes; and

30 Fig. 5 is a transverse section of a sluice box, taken on line 5—5, Fig. 3.

In the drawings numeral 1 represents the surface of the ground that is to be worked, and 2 represents in a general way the truck 35 that has one end supported on wheels 3 and the other supported on a track laying traction assembly 4 of the type employed in connection with that type of tractor usually designated as caterpillar tractor. Supported 40 on the truck is an internal combustion engine 5 that has merely been indicated in a dia- grammatic manner. This engine serves to produce power for operating the machine, as well as for transporting it when it is 45 moved. Secured to the front end of the truck is a boom 6 that has one end pivoted so that it can be rotated about the axis 7 and which carries a conveyor belt 8 to which digging buckets 9 are attached. By means of 50 the engine, the conveyor is operated so that

the under surface thereof moves upwardly in the direction of the arrow. The buckets of the conveyor carry sand and gravel upwardly and deposit the same on a transverse conveyor 10 that in turn deposits the material 55 in a hopper 11 having a spout that projects into the upper end of a rotating screen cylinder 12. Located underneath this cylinder is a hopper 13 and a launder 14 extends from the delivery end of the cylinder downwardly 60 so as to convey the coarse material to one side. Located underneath the hopper 13 is a separator comprising a casing having a top wall 15 and side walls 16. At one end of this casing I have located a blower 17 within 65 which is mounted a fan having blades 18. This fan is rotated in a clockwise direction and delivers a strong breeze through the nozzle 19. A plurality of screens, of which three sections A, B and C have been shown, 70 are supported from the sides 16 by means of links 20. The upper ends of these links are pivotally connected with the sides and the lower ends with the side members 21 of the screen frames. Each frame is provided with 75 a screen bottom 22 which may be the same mesh for all of the screens if desired. A connecting rod 23 has one end connected with a bracket 24 on the under surface of screen section B and the other connected with an eccentric 25 on the shaft 26 of the fan. The several screen sections are interconnected by 80 means of links 27 so that they will reciprocate as a unit. When the fan is rotating the screens will reciprocate and material will 85 pass from the discharge opening of hopper 13 outwardly over the screens and be discharged therefrom at end 27. Located beneath the screens are four screw conveyors 28, 29, 30 and 31. Extending upwardly from the cas- 90

ings surrounding the screw conveyors 28, 29 and 30 are inclined partitions 32, 33 and 34 respectively. The upper end of partition 34 is connected with the casing surrounding the conveyor 31; while the other partitions 95 terminate above the next outwardly located conveyors. When the fan is operating material will pass through the screens and as this falls through the strong air current that is produced by the fan, the lighter materials will be 100

carried outwardly, while the heavier materials will pass through the air currents and onto the partitions 32, 33 and 34. The very light materials, such as flour gold will be carried along until it reaches the end conveyor 31 where it will be intercepted by the end wall 35 and accumulate about the conveyor which as it rotates moves the material outwardly towards one side. From one or all of the conveyors 28, 29 and 30, values can be obtained, and it is therefore desirable to pass the materials that accumulate in these conveyors through a sluice box where the metallic values can be separated in the usual manner. Since the space available for the sluice boxes is limited, they have been made of several short sections and in the drawings a three-part sluice box has been illustrated. The upper, intermediate and lower sluice box sections have been designated respectively by reference numerals 36, 37 and 38. For the purpose of supporting these boxes, vertical beams 39 have been provided. There is one beam on each side of the sluice boxes at each end thereof and the sluice boxes are supported from these beams by means comprising shafts 40 and links 41. The higher end of the section 36 is connected with the lower end of section 37 by means of links 41 that have their upper ends pivotally connected with sluice box section 36 and their lower ends with sluice box section 37 and the upper end of sluice box section 37 is similarly connected with the lower end of sluice box section 38. Secured to the frame member 42 is a shaft 43 that is provided at one end with a belt wheel 44 with which the belt 45 cooperates. This belt has its upper end associated with a pulley on the end of the fan shaft 26 and when the fan rotates, the sluice boxes will be reciprocated. I find that the best results are obtained when the sluice boxes have a sidewise motion as well as a longitudinal motion and in order to obtain movement simultaneously in two directions, I have secured to one of the supporting beams 39 a bracket 46 that has a portion inclined towards the sluice box and the latter is provided with a block 47 that contacts with the inclined inner surface of the bracket and therefore the sluice box is given a transverse movement as well as a longitudinal movement, when it is reciprocated. Shaft 43 is provided with an eccentric 48 and a connecting rod 49 has one end connected with the eccentric and the other pivotally connected at 50 to the upper end of section 36, and therefore when the fan is rotated, the sluice boxes will be reciprocated and will also move transversely and since they are supported on links 50, they will also have movement in an arc and these three movements give to the sluice boxes a motion that corresponds quite closely to the motion that a miner gives to a pan when panning gold. In order to facilitate the cleaning up of the sluice boxes the latter

have been provided with removable pans 51 that are formed from short sections and the bottoms of these pans may be provided with cleats 52 as illustrated or they may have a covering of carpet or wires or some of them may even be formed by amalgamated copper plates. When the sluice boxes are to be cleaned the pans are removed and replaced by others, and therefore it is not necessary to close down the machine for any considerable length of time because the pans can be quickly removed and replaced. 70

The water for the separation that takes place in the sluice boxes is supplied through a pipe 51a like that shown in Fig. 2. This pipe may be connected with a pump or with any source from which water can be obtained. 80

Since this machine is power operated and digs and elevates the sand and gravel, it is possible for one man to operate the entire 85 machine and therefore the cost of handling a ton of material is greatly decreased.

Since the flour gold and other light metallic particles are carried along by the air currents and deposited in the housing of 90 screw conveyor 31, the materials that are delivered by this conveyor are usually rich in gold values, and since the material in this conveyor is very light, it is not suitable for treatment in the sluice boxes. 95

The parts are so arranged that either or all of the conveyors, 28, 29 and 30, can be connected with the sluice boxes so that all of the values can be removed from the sand and gravel. 100

In some cases it is unnecessary to separate the materials by means of the air separator and when this is found to be the case, the latter can be removed and the material from hopper 13 can be discharged directly into 105 the sluice boxes.

Where the sand and gravel contains considerable quantities of flour gold the air separator shown and described is quite necessary for the best results as flour gold is so light that it will float on water and will therefore be lost if it is introduced with other material into the sluice boxes. 110

From the above description it will be seen that I have produced a mining machine that is self-contained and power operated, and which can be operated by one man if necessary. This machine is mounted on a truck that will travel by its own power and can therefore be readily transported from one place to another and by virtue of its air separator, it is possible to save a large percentage of the flour gold and other fine values that would otherwise be lost. 115

Having described the invention what I 125 claim as new is:

A placer mining machine for separating metallic particles from nonmetallic material containing the same comprising, in combination, a frame, a screen carried thereby, 130

means for delivering material to the screen, a hopper located beneath the screen and adapted to receive the screenings, a separator located beneath the hopper, the separator comprising a sectional screen, means comprising links for suspending the screen, means for reciprocating the screen, means for directing an air current along the bottom of the screen whereby any material passing through the screen will be separated in accordance with its weight, a plurality of transversely extending conveyors located underneath the screen, inclined bottoms for directing materials to the conveyors, a sluice box located underneath the transverse conveyors, and means for reciprocating the sluice boxes and for imparting to them a transverse movement.

In testimony whereof I affix my signature.
